CLAIM

The ornamental design for a vehicle article carrier stanchion, as shown and described.

DESCRIPTION

FIG. 1 is an outer perspective view of a vehicle article carrier stanchion showing our new design;

FIG. 2 is an inner perspective view thereof with a lever forming part of the stanchion shown in a closed position;

FIG. 3 is an inner perspective view thereof with the lever shown in an open position;

FIG. 4 is an outer side elevation view thereof to a reduced scale;

FIG. 5 is a top plan view thereof;

FIG. 6 is an inner side elevation view thereof;

FIG. 7 is a bottom plan view thereof;

FIG. 8 is an end elevation view thereof taken along line 8—8 of FIG. 6; and

FIG. 9 is an end elevation view thereof taken along line 9—9 of FIG. 6.

The broken lines in the drawing are for illustrative purposes only and from no part of the claimed design.

Fig. 8.
